UNITED STATES PATENT OFFICE.

LOUIS J. WESTNESS, OF MILWAUKEE, WISCONSIN.

SASH-CORD HOLDER.

1,268,194.

Specification of Letters Patent.

Patented June 4, 1918.

Application filed February 23, 1918. Serial No. 218,762.

To all whom it may concern:

Be it known that I, LOUIS J. WESTNESS, a citizen of the United States, and resident of Milwaukee, Milwaukee county, Wisconsin, have invented new and useful Improvements in Sash-Cord Holders, of which the following is a description, reference being had to the accompanying drawings, which are a part of this specification.

10 This invention has for its object to provide a window sash cord holder which may be conveniently clamped on the sash cord to temporarily relieve the sash of the influence of the sash weight or spring at such times as when the sash is disconnected from the sash cord for cleaning or repair.

The present application constitutes a continuation in part of application Serial No. 52,825, filed September 27, 1915, for de-20 mountable windows.

With the above and other objects in view, the invention consists in the sash cord holder as herein claimed and all equivalents.

Referring to the accompanying drawings, 25 in which like characters of reference indicate the same parts in the different views:

Figure 1 is a view of a window showing the sash cord holder of this invention in use while the window sash is swung on pivotal 30 connections to remove it from the window frame for cleaning;

Fig. 2 is a detail view of the sash cord holder on a larger scale;

Fig. 3 is a sectional view showing the 35 manner of engagement of the holder with the sash cord; and,

Fig. 4 is an edge view of a window sash equipped for readily disconnecting the sash cord and attaching the sash cord holder in 40 the manner shown in Fig. 1.

In these drawings 10 indicates a window frame having upper and lower window sash 11 slidably mounted therein and counterbalanced by being suspended from sash 45 cords 12 which pass over grooved pulleys 13 let into the window frame and connecting with sash weights 14 traveling within the hollow window frame, all as usual.

The window shown is equipped on one 50 side with suitable pivotal connections 15 capable of adjustment for the engagement of its parts in one position of the sash and having the sash stop on the other side removable to permit the sash to be swung out

of its sliding bearings in the frame and into 65 the room to render both sides thereof accessible for cleaning. At such times it is very desirable to disconnect the sash cord from the free or outer edge of the sash or to otherwise overcome the tendency of the sash 60 weight to pull the sash back into the window frame. It is also desirable to provide means for holding the sash cord in its withdrawn position, that is the position in which it was disconnected from the sash, for otherwise the weight will descend and carry the end of the cord out of reach and will sometimes cause the cord to break, or the knot on the end thereof to slip through the pulley housing so that it is difficult to make repairs. 70 The sash cord holder of this invention is provided for this purpose.

A rod, forming a handle 16 of suitable length, has secured to one end a metal blade 17 which is preferably V-shaped in cross-section with its trough or channel parallel with the handle. The blade extends to one side of the handle and its front end is provided with a V-shaped notch 18 to facilitate its engagement with the sash cord and to permit 80 the blade to fit closely between the sash cord and the pulley 13. The bottom of the trough is made wedge-shaped for a short distance with the point of the wedge at the crotch of the notch 18 and when the blade 85 is formed of sheet metal as here shown that portion which is cut to form the V-shaped notch is not entirely severed but the two lines of cut terminate a short distance from each other and the tongue of metal between 90 them is bent into the trough to produce the wedge referred to and is held in place preferably by means of a rivet 19 passing through it and the bottom of the trough. The lower end of the wedge forms an abrupt 95 shoulder 20 in the channel of the trough over which the sash cord passes. A crank pin 21 is journaled in a groove in the handle 16 being held within the groove by the blade 17. One end is bent to form a V-shaped 100 crank fitting the channel of the trough 17 and bearing against the shoulder 20, while the other end is bent to form a crank arm which is connected by a connecting rod 22 with an angular lever 23 pivotally mounted 105 on the other end of the handle. At an intermediate point the connecting rod 22 is bent to form an eye for engagement with

one end of a coil spring 24, the other end of which is connected to the handle so that the spring tends to pull the connecting rod 22 and turn the crank pin 21 so as to hold its end against the shoulder 20.

5 To engage the sash cord holder the lever 23 is pressed against the handle, thereby pushing the connecting rod 22 against the action of the spring 24 to swing the crank 10 pin 21 away from the shoulder 20. The hook formed by the blade is then passed behind the sash cord and is pushed upwardly until it bears against the pulley 13 when the lever 23 is released permitting the 15 spring 24 to move the crank pin into engagement with the sash cord and sharply bend it around the shoulder 20, as shown in Fig. 3. This clamping engagement of the holder with the cord, together with the bearing 20 of the holder against the sash pulley, prevents the return of the sash cord under the influence of the sash weight and leaves the knotted end of the sash cord where it may conveniently reengage with the sash 25 when it is desired to return the sash to the window frame.

In using the device with window sash pivotally swung from the window frame, as shown in Fig. 1, it is not only desirable that 30 both sash cords should be secured in this manner by the sash cord holder, but it is desirable that the sash cord holder at the side of the window sash which is pivotally mounted should be utilized as a means for 35 suspending the other side of the window sash. For this purpose a coil spring is connected at one end to an eye 26 on the end of the handle 16 and at the other end to an eye 27 secured to the sash. This serves to 40 support the sash at both sides thereof and avoid a racking tendency that would be incident to the pivotal connection without such additional support, particularly with a very wide sash or a weakened sash.

45 To facilitate the removal and attachment of the knotted end of the sash cord, the opening in the end of the groove at the side of the sash may be provided with a pair of inclined parallel pins 28 between which the 50 knot may be readily slipped.

The sash cord holder of this invention is quickly applied or detached and makes a strong clamping engagement with the sash cord which tends to increase its hold under 55 the pull of the sash weight and make the use of stepladders unnecessary in the window cleaning operation. It is inexpensive to manufacture and strong and durable.

What I claim as new and desire to secure 60 by Letters Patent is:

1. A sash cord clamp, comprising a handle member, a hook member thereon of a U-shape in cross section and having a V-shaped notch to fit over the sash cord, a shoulder 65 on the hook member, a crank pin on the

handle member having a crank portion to clamp the sash cord between it and the shoulder of the hook member, a spring-actuated connecting rod connected with the crank pin, and a lever on the handle connected with the connecting rod. 70

2. A sash cord holder, comprising a handle member, a metal blade secured thereto and having a groove formed therein with a notch at its end, said notch being adapted 75 to be engaged with the sash cord near its pulley, and a clamping member on the handle having means for moving it with spring pressure toward the blade to clamp the sash cord therebetween. 80

3. A sash cord holder, comprising a handle, a blade secured to one end of the handle and bent to form a channel with a notch in its end to receive the sash cord near the pulley, a crank pin on the handle having a bent end co-operating with the blade to form a clamp therewith, a lever on the other end of the handle, and a connecting rod connecting the lever with the crank pin. 85

4. A sash cord holder, comprising a handle, a blade secured to one end thereof and bent to form a trough, a shoulder in the bottom of the trough, a crank pin having a bent portion adapted to enter the trough and form a clamp therewith for engaging the sash cord, and an operating means connected with the crank pin for turning it to its clamping position. 90

5. A sash cord holder, comprising a handle, a sheet metal blade secured to one end thereof and bent to form a channel with a notch formed at one end by means of a pair of converging slits, the tongue of metal between the slits being bent into the channel and secured thereto and forming a shoulder 100 at its end, a clamping member mounted on the handle and adapted to engage the sash cord between it and the shoulder, and means for operating the clamping member. 105

6. A sash cord holder, comprising a handle, a sheet metal blade secured to one end thereof and bent to form a channel with a notch at one end formed by converging slits with the tongue of metal between them bent into the channel and riveted thereto to form 110 a shoulder across the channel, a crank pin journaled in a groove of the handle and lying between the handle and the blade with one end bent to form a clamping member co-operating with the shoulder and the channel 115 to form a clamp for the sash cord and the other end bent to form a crank, an angular lever pivotally mounted at the other end of the handle, a connecting rod connecting the angular lever with the crank arm of the crank pin, and a spring connected between the rod and the handle. 120

7. A sash cord holder, comprising a handle provided with a clamping means at one end thereof for grasping and holding the 125 sash cord. 130

sash cord, and a flexible connection on the other end of the handle for connection with the window sash.

8. A sash cord holder for use with sliding window sash, provided with pivotal connections at one side for use in removing the sash from the window frame, comprising a handle having a clamping means at one end for engaging the sash cord and an operating means for said clamping means at the

other end, and a coil spring connected to said other end of the handle and adapted to be connected to the outer end of the window sash.

In testimony whereof, I affix my signature, in presence of two witnesses.

LOUIS J. WESTNESS.
